UNITED STATES PATENT OFFICE.

RICHARD LA FRANCE, OF TOLEDO, OHIO, ASSIGNOR TO THE OWENS BOTTLE MACHINE COMPANY, OF TOLEDO, OHIO, A CORPORATION OF OHIO.

GLASS-FORMING MACHINE.

1,348,365.

Specification of Letters Patent. Patented Aug. 3, 1920.

Application filed September 4, 1917. Serial No. 189,458.

To all whom it may concern:

Be it known that I, RICHARD LA FRANCE, a citizen of the United States, residing at Toledo, in the county of Lucas and State of Ohio, have invented new and useful Improvements in Glass-Forming Machines, of which the following is a specification.

This invention relates to machines for forming bottles or other glass articles which are blown or otherwise formed in molds on the machine. An object of the invention is to provide an improved mechanism for holding bottles or other articles during the opening of the finishing molds and controlling said articles in their discharge from the molds. The invention is herein shown as embodied in an automatic bottle blowing machine of the "Owens" type, particularly designed for making carboys or other bottles or containers of large capacity. Certain features of the invention are particularly adapted for use in connection with machines for making such ware.

Other objects of the invention and the exact nature thereof will appear hereinafter.

In the accompanying drawings:

Figure 1 is a sectional elevation of a portion of the machine at the right hand side of the vertical center line.

Fig. 2 is a part sectional elevation showing an open blow mold and associated mechanism.

Fig. 3 is a part sectional plan view showing the "knock-out" device, the blow mold and its operating means.

Fig. 4 is a part sectional elevation of the "knock-out" device.

Fig. 5 is a plan view of the same.

Fig. 6 is a sectional plan view of mechanism shown in Fig. 4.

Figs. 7 to 12 inclusive are diagrammatic views of the "knock-out" device, Figs. 7, 9 and 11 being plan views of the arm at successive steps in its operation, Figs. 8, 10 and 12 being elevation views with the parts positioned as in Figs. 7, 9 and 11 respectively.

Fig. 13 is an elevation view of a bank of valves.

Fig. 14 is a sectional elevation of a valve and its operating cam.

The machine frame comprises a central non-rotating column 31 made in sections, and on which is mounted the main rotating frame 32. The frame 32 runs on bearing rolls 33 and is driven through a ring gear

34 connected to any suitable source of power. On the rotating frame are mounted a number of units or mechanisms, preferably arranged at equal intervals around the machine, and each comprising a blank-mold, a blow-mold and coöperating devices for forming the bottles.

The blank-molds 35 (Fig. 1) are arranged above the level of the gathering tank 36 from which the glass is drawn, so that each blank-mold is brought over the tank once during a complete rotation of the machine. In order to dip the molds into the molten glass for gathering a charge as they pass over the tank, the molds are mounted on individual dipping heads or frames 37. The vertical movement of the dipping heads is controlled by a stationary cam track 38 in which runs a cam roll 39 connected through a link 40 to the vertical arm of a bell crank 41, pivoted at 42 to the frame 32. The horizontal arm of the bell crank is connected at 43 to a link 44 attached to an adjusting rod 45 on the dipping head.

The cam track 38 is shaped to draw the cam roll 39 toward the center of the machine as the blank mold moves over the tank, and thereby lower the mold to receive a charge of glass. The dipping head is counter-balanced by a weight 46 connected through a lever 47 to the link 44. The counter-weight is supplemented by a counterbalancing spring 48. The weights 46 extend downward within the hollow stationary column 31 and revolve with the main frame 32.

The glass is drawn by suction or differential pressure into the gathering mold to form a parison which is afterward transferred to a blow-mold and blown to form the completed bottle. The gathering mold comprises the body blank mold 35 and a neck mold 49, each consisting of two halves or sections mounted to swing horizontally about a common pivot pin 50.

The means for operating the body blank mold 35 comprises a piston motor 51 operated by compressed air or steam. The motor drives a rack 52 connected through suitable mechanism to open and close the mold sections.

The neck mold 49 is opened and closed by a motor 58.

A core or plunger 63 for forming the initial blow opening in the parison, is connected to a plunger rod 65 to the upper end

of which is attached the piston of an operating motor 66. When the parison mold is in gathering position, (Fig. 1), the air is exhausted from the mold cavity through exhaust passages leading through the suction and blowing head 67, the latter being in communication with a suitable vacuum chamber. The glass is thereby forced into the mold cavity by atmospheric pressure to 5 form a parison. The neck mold cavity is shaped to give the neck of the bottle its final form.

After the glass is drawn into the mold and the neck portion of the bottle formed in 10 the neck mold, the motor 66 is operated to withdraw the plunger. A rack 68 attached to the plunger rod is thereby moved upward and rocks a toothed segment 69 which meshes with said rack. The segment 69 is pivoted 15 at 70 and is provided with a cam groove which engages a wrist on a lever 72 to operate a slide valve 73 connected to said lever. The cam 71 is so formed that as the plunger is withdrawn, the valve 73 is slid over the 20 opening in the head 67.

About the time the plunger is withdrawn, or shortly before, the motor 51 operates to 25 separate the body blank mold sections 35, leaving the blank suspended from the neck 30 mold. The blow mold is also moved up (as hereinafter described) to receive the blank and inclose the same immediately after the blank mold opens. Air under pressure is then admitted through the valve 73 and head 35 67 to the opening formed in the blank by the core 63, and the bottle is blown to its final shape.

As the blank mold is withdrawn from the gathering tank, a suitable knife or cut-off 40 (not shown) is operated to sever the blank in the mold from the glass in the tank.

Each of the blow molds 97 is carried on a frame 98 mounted for vertical movement in guideways 99 on the main rotating frame 45 32. The blow mold while idle travels in a horizontal path below the tank 36. After a blank mold with its gather of glass, passes beyond the tank, the coöperating blow mold is lifted to the plane of the blank mold to 50 receive the blank. For this purpose air under pressure is admitted beneath the piston 100 of a motor 101 mounted on a bracket 102 on the frame 32.

A bottom plate 103 provides a support 55 for the blank while the latter is suspended from the neck mold and also provides a bottom for the blow mold. The bottom plate is carried at the upper end of a piston rod 104 of a motor 105 mounted on 60 the bracket 102. Pressure is admitted beneath the piston of the motor 105 to lift the bottom plate 103 and cause it to engage with the bottom of the blank mold and blank therein, just after the cut-off has been 65 withdrawn and before the blank mold opens.

The blank is thereby supported during its transfer from the blank mold to the blow mold, and prevented from being thrown out of vertical alinement by the vibration of the machine, or drawing downward by its own 70 weight.

The blow mold 97 is made in sections mounted to swing on a vertical pivot rod 106 on the frame 98, and while open (Figs. 2 and 3) is moved upward between the 75 blank and the blank mold sections just after the latter have opened. The blank is at this time suspended from the neck mold 49, the bottom of the blank resting on the bottom plate 103. The blow mold is closed 80 by motors 107 (see Fig. 4) on the frame 98. Each motor is connected to a mold section through gearing comprising a rack 108 attached to the motor piston and meshing with a gear segment 109 on a rock-shaft 85 110 to which is secured a rock-arm 111 connected through a link 112 to the mold section. A pair of intermeshing gears 212 insure equal movement of the two mold sections, and may also be used if desired to 90 transmit motion from one rack to the other so that a single motor 107 will operate both mold sections.

When the blank is inclosed in the blow mold, and the plunger 63 has been withdrawn and the slide valve 73 advanced 95 air under pressure is admitted and the parison blown to form the bottle B. After the bottle is blown, the neck mold is opened by its motor 58, leaving the bottle free to be 100 lowered with the finishing mold, which is now carried downward by admitting pressure above the piston 100. The mold bottom is lowered with the mold by admitting 105 pressure above the piston of its motor 105.

The mechanism for engaging the top of the bottle or other blown article and holding it during the opening of the finishing mold, will now be described. This mechanism comprises an arm 150 (known in the trade as a "knock-out" arm) which normally extends at one side of the mold position but is arranged to swing horizontally to extend over the mold and also has a short vertical movement bodily into and out of contact 110 with the bottle. Said arm also has a vertical swinging movement about its pivot 151 for a purpose which will be described later. The arm and its actuating mechanism are mounted on the blow mold frame 98 to move 115 up and down with the blow mold. Said mechanism is also adjustable vertically relative to the blow mold by rotating a hand wheel 152 carried by a sleeve 153 threaded on a vertical rod 154 on the frame 98. Said sleeve is thereby adjustable up and down 120 and carries with it a bracket 155 slidable vertically in ways 156 on the frame 98. The bracket 155 carries at its lower end a piston 125 motor 156 comprising a piston 157 and pis- 130

ton rod 158, the latter extending upwardly through a hollow cylindrical portion 159 of the bracket 155 and through a cylindrical carrier 160, on which the arm 150 is mounted. The carrier 160 is slideable up and down in a sleeve or cylindrical bearing 161 on the bracket 155.

The upward movement of the arm 150 about its pivot 151 is limited by a stop 251. 5 The arm is normally held up by a coil spring 162 on a link 163 comprising telescoping sections. Rotation of the arm 150 about a vertical axis is controlled by a wrist pin 164 on the piston rod 158, said wrist pin 15 working in a cam slot 165 formed in the section 159 of the bracket. As the piston moves vertically it is also given a rotary movement by means of the cam, said rotation being imparted to the carrier 160 by 15 means of a pin 166 carried by the piston rod and working in a vertical slot 167 in the carrier 160.

The arm 150 carries a head 169 to which is clamped a disk 170 formed of asbestos or 25 other suitable material for engaging the neck end of the carboy. The head 169 can yield upwardly against the tension of a spring 173 and is also adjustable vertically with its carrying member 171, the latter being clamped in its adjusted position in the split end of the arm by a clamping bolt 172.

The operation of the holding arm 150 is as follows:—

Normally said arm is tilted downward to 35 the Fig. 8 position to permit the arm to clear the bottom 176 of the tank and also to clear a portion of the neck mold mechanism. The arm is held in such tilted position by the piston rod 158 which at this time is in its 40 uppermost position. After the carboy B is blown, the finishing mold with the carboy in it moves downward as before described. The "knock-out" mechanism being mounted on the mold carrier frame 98 moves downward with the mold. As soon as the carrier 45 has moved away from the blowing head, compressed air is admitted through pipe 175 (Fig. 8) to the upper end of the cylinder 156. The piston 157 and piston rod 158 are thereby caused to descend, and during 50 the initial downward movement the piston rod is withdrawn from the arm 150 so that the spring 162 swings said arm upward to the Fig. 10 position. During this initial 55 movement the wrist pin 164 moves in a vertical portion of the cam slot. As the piston continues its downward movement, the wrist is moved through the spiral intermediate portion of the slot so that the piston rod is given a spiral movement, thereby 60 swinging the arm 150 laterally and bringing the head 169 over the bottle in the finishing mold. The pin 166 engages the bottom of the slot 167 before the piston reaches the 65 bottom of its cylinder, so that during the

final downward movement of the piston the sleeve 160 is pulled downward, compressing the spring 177 and moving the disk 170 downward against the neck of the bottle. The lower end of the cam slot is also vertical 70 so that the arm 150 moves vertically downward. The disk holds the bottle until the finishing mold has opened wide enough to clear the bottle. The valve controlling the motor 156 is then reversed, permitting air 75 pressure beneath the piston, which as it rises, permits the spring 177 to lift the sleeve 160, thus raising the contact disk 170 away from the bottle. The wrist pin 159 then enters the spiral portion of the cam and 80 swings the arm laterally away from the finishing mold. The bottle is now free to be removed by an attendant. The piston continues its upward movement to the end of its stroke, the latter part of which causes the 85 piston rod to reengage the swinging arm 150 and tilt it downwardly where it is held until it commences another cycle of operations.

Each of the several piston motors associated with a bottle forming unit is controlled by an individual valve such as shown in Fig. 14, and the valves for each unit are preferably grouped together as indicated in Fig. 13. This group comprises a valve *a* 90 controlling the neck mold operating motor 58, a valve *b* for the blank mold motor 51, a valve *c* for the plunger motor 66, a valve *d* for the finishing mold motors 107 (Fig. 3) which actuate the finishing mold sections, a valve *e* for the motor 156 (Fig. 4) which 100 operates the "knock-out" arm 150, a valve *f* for the cut-off motor not shown, a valve *g* for the motor 101 (Fig. 1) which lifts the finishing mold, and a valve *h* for the motor 105 which operates the mold bottom plate 105 103. Air under pressure for operating the motors may be supplied through a pressure pipe 116 (Fig. 13) from which it is distributed through branch pipes 116' to the several valves which control the supply of 110 compressed air to their respective motors.

The valves are preferably substantially alike in construction, which may be as shown in Fig. 14. Compressed air is admitted from the supply pipe 116 and a branch pipe 116' 115 to an intermediate port or chamber 117 in the valve casing, which port is brought into communication alternatively with the end ports 118 and 119 by the movement of the valve piston 120. The ports 118 and 119 120 communicate respectively with the opposite ends of the corresponding motor cylinder. Thus, as shown in Fig. 14, the valve piston 120 is in position to open the port 118 to the port 117 so that compressed air is supplied 125 through port 118 to one end of the motor 58. The port 119 is at the same time open through a passage 121 with the atmosphere. When the valve 120 is moved to the left, the pressure port 117 is opened to port 119 130

admitting compressed air to the opposite end of the motor cylinder. At the same time communication between the port 119 and the outside air through passage 121 is cut off, by valve 120, and the port 118 opened to atmospheric pressure through passage 122.

The valve stem 123 carries a cam roll 124 running in a guideway in a cam plate 125. 10 Each of the cams 125 for the several valves is mounted on the stationary column 81, the cams being secured in grooves 126 formed in said column one above another, as indicated in Fig. 1. It will be understood that the cams 125 for operating the valves are so positioned and formed that the several operations controlled thereby take place in the proper sequence and at the required time. The method of mounting the 20 cams 125 permits each cam to be readily and accurately adjusted or replaced by another cam without interference with the other cams. It will be understood that the several sets of valves are all controlled by a single 25 set of cams.

Variations may be resorted to without departing from the spirit and scope of my invention.

What I claim is:—

- 30 1. The combination with a finishing mold, of a holding device to engage an article in the mold and hold it during the opening of the mold, a piston motor, and means operated and controlled thereby to move the 35 holding device laterally to a position over said article during a portion of the piston stroke and downward into engagement with said article during another portion of said stroke.
- 40 2. The combination with a finishing mold, of a holding arm to engage an article in the mold and hold it during the opening of the mold, a carrier on which the arm is pivotally mounted, means to rotate said carrier 45 to swing the arm laterally, means for raising and lowering the carrier to move the arm up and down bodily, and means to swing said arm about its pivot on the carrier.
- 50 3. The combination with a finishing mold, of a holding arm to engage an article in the mold and hold it during the opening of the mold, a carrier on which the arm is mounted to swing up and down, means to 55 rotate said carrier to swing the arm laterally, means for raising and lowering the carrier to move the arm up and down bodily, and means to swing said arm downward on said carrier while positioned laterally of the 60 mold.
- 65 4. The combination with a mold, of a holding arm to engage an article in the mold and hold it during the opening of the mold, a piston motor, and means actuated thereby to impart an up or down movement

to said arm during a portion of the piston stroke and to swing said arm laterally about the axis of the piston during another portion of the piston stroke.

5. The combination with a finishing mold, 70 of a holding arm to engage an article in the mold and hold it during the opening of the mold, a motor for actuating said arm comprising a piston and piston rod, means actuated by the motor to swing said arm laterally about the axis of the piston rod during a portion of the piston stroke to position said arm over the mold, and means operable during another portion of the piston stroke to move said arm downward to engage said 80 article.

6. The combination with a finishing mold, of a holding arm to engage an article in the mold and hold it during the opening of the mold, a carrier on which said arm is 85 mounted, a piston motor comprising a piston rod, connections between piston rod and carrier for moving the latter with the rod during a portion of its stroke, and means for rotating said carrier during another 90 portion of the piston stroke.

7. The combination with a finishing mold, of a holding arm to engage an article in the mold and hold it during the opening of the mold, a carrier on which said arm is 95 mounted, a piston motor comprising a piston rod, connections between piston rod and carrier for moving the latter with the rod during a portion of its stroke, and means for rotating said piston rod and carrier during 100 another portion of the piston stroke.

8. The combination with a finishing mold, of a holding arm to engage an article in the mold and hold it during the opening of the mold, a carrier on which said arm is 105 mounted, a piston motor comprising a piston rod, connections between piston rod and carrier for moving the latter with the rod during a portion of its stroke, a cam, and connections between said cam and carrier for 110 rotating the latter during a portion of the piston stroke, to swing said arm laterally toward or from a position over the mold.

9. The combination with a finishing mold, of a holding arm to engage an article in the mold and hold it during the opening of the mold, a carrier on which said arm is mounted, a piston motor comprising a piston rod, connections between piston rod and carrier for moving the latter with the rod 115 during a portion of its stroke, means for rotating said carrier during another portion of the piston stroke, and means actuated by the motor for tilting said arm.

10. In a glass forming machine, the combination of an arm, a head thereon for engaging and holding an article formed on said machine, a piston motor comprising a piston rod movable up and down, a carrier on which said arm is mounted, and a lost 125 130

- motion connection between the piston rod and carrier for imparting an up or down movement to the carrier during a portion of the piston stroke, and permitting up and down movement of the piston relative to the carrier during another portion of the piston stroke, and means for rotating said carrier to swing the arm laterally during said last mentioned portion of the piston stroke.
11. In a glass forming machine, the combination with an arm for holding an article formed on the machine, of a piston motor, a carrier on which said arm is mounted, said carrier arranged for bodily movement lengthwise of the motor piston and rotative movement about the axis of the piston, means operated by the motor to rotate said carrier and swing said arm laterally during a portion of the piston stroke, and means to connect the carrier with the piston for bodily movement therewith during another portion of the piston stroke.
12. The combination in a glass forming machine, of an arm to engage articles formed on the machine, a piston motor comprising a piston rod, a carrier on which the arm is supported, said carrier slidable on said rod, a slot and pin connection between the carrier and rod for moving the carrier with said rod during a portion of the piston stroke and permitting the rod to move lengthwise in the carrier during another portion of its stroke, and a cam arranged to rotate the piston rod and carrier while said rod moves lengthwise in said carrier.
13. The combination in a glass forming machine, of a carrier, an arm extending laterally therefrom for holding an article formed on the machine, a piston motor comprising an upwardly extending piston rod on which the carrier is mounted for movement lengthwise of the rod, said carrier having a limited up and down movement, a spring to hold the carrier in its upward position, a slot and pin connection between the piston rod and carrier, a cam arranged to rotate the piston rod during a portion of its downward stroke, and thereby rotate said carrier and arm to swing the arm laterally to a position over the article to be held, the piston being operable through said slot and pin connection to move the carrier downward against the tension of said spring during the final portion of the piston stroke and thereby move the arm downward to engage the said article.
14. The combination in a glass forming machine, of a carrier, an arm extending laterally therefrom for holding an article formed on the machine, a piston motor comprising an upwardly extending piston rod on which the carrier is mounted for movement lengthwise of the rod, said carrier having a limited up and down movement, a spring to hold the carrier in its upward position, a slot and pin connection between the piston rod and carrier, a cam arranged to rotate the piston rod during a portion of its downward stroke, and thereby rotate said carrier and arm to swing the arm laterally to a position over the article to be held, the piston being operable through said slot and pin connection to move the carrier downward against the tension of said spring during the final portion of the piston stroke and thereby move the arm downward to engage the said article.
15. The combination with a finishing mold, of a holding arm to engage an article in the mold and hold it during the opening of said mold, automatic means to move the arm toward and from said article into and out of position to hold the article, and means to swing the arm transversely into and out of position over the article without movement in said first mentioned direction.
16. The combination with a finishing mold, of a holding arm to engage an article in the mold and hold it during the opening of the mold, a piston motor, and operating connections between said arm and the motor, including means for moving the arm in a direction toward and from said article and for swinging the arm laterally without movement in said first mentioned direction.
17. The combination of an arm to engage an article in a mold and hold it during the opening of the mold, a piston motor, and operating means between the motor piston and said arm for moving the latter bodily to and from said article during a portion of the piston stroke and including a cam for swinging the arm laterally during another portion of the piston stroke without movement of said arm in the direction of said bodily movement.

Signed at Toledo, in the county of Lucas 110
and State of Ohio, this 31st day of August,
1917.

RICHARD LA FRANCE.
